UNITED STATES PATENT OFFICE.

JOHN WESLEY HOFFNER, OF SALISBURY, NORTH CAROLINA.

AUTOMATIC AUTOMOBILE ENGINE-STARTER.

1,165,506.

Specification of Letters Patent. Patented Dec. 28, 1915.

Application filed December 11, 1914. Serial No. 876,709.

To all whom it may concern:

Be it known that I, JOHN W. HOFFNER, a citizen of the United States, residing at Salisbury, in the county of Rowan and 5 State of North Carolina, have invented certain new and useful Improvements in Automatic Automobile Engine-Starters, of which the following is a specification.

This invention relates to the subject of 10 automatic starters for internal combustion engines, and has particular reference to a novel device of this character that is especially adapted for use in connection with automobile engines. Many devices of this 15 character employing spring motors are very complicated and need constant attention and repair, thereby reducing their practical value and prohibiting a general adoption of this type of device for starting the engines of motor cars.

Accordingly, the present invention has in view the provision of a novel, simple, and practical construction which embodies few parts other than essential substantial gears 25 and a double strength spring motor having suitable operating connections with said gears, thereby providing a reliable and efficient starter.

Another object of the invention is to provide a starter which will be automatically rewound and reset by the engine after the latter has been set in motion by the starter, and to also provide for rewinding the spring motor by hand if the engine should 35 be at fault and not respond to the action of the present device. That is to say, if the engine does not run under its own power to automatically rewind the spring driving motor, the invention contemplates means for 40 rewinding the said motor by hand so that it may again be reset for further spinning of the engine shaft.

A further object of the invention is to provide an engine starter that may be 45 readily fitted to machines now in use as well as to cars when they are built, and which will in no way interfere with the cranking of the engine by hand when desired or should the starter itself refuse to properly 50 spin the engine shaft. In other words, the present invention contemplates a starter having no operative connection with any portion of the engine except the drive shaft, and that only when the device is turning the 55 said shaft and when the engine is rewinding the spring motor after it has started.

With the above and other objects in view, the invention consists in the novel construction, combination, and arrangement of parts hereinafter more fully described, illustrated 60 and claimed.

A preferred and practical embodiment of the invention is shown in the accompanying drawings, in which—

Figure 1 is a top plan view of the present 65 invention, showing its application to an internal combustion engine indicated by dotted lines. Fig. 2 is a side elevation of the construction shown in Fig. 1. Fig. 3 is a front elevation of the improved starter. 70 Fig. 4 is a cross sectional view on the line 4—4 of Fig. 1 showing the relative position of parts when the oscillating bracket element is in its neutral position. That is when the pinion of the engine shaft is out 75 of engagement entirely with the starter. Fig. 5 is a view similar to Fig. 4 showing the relative position of parts when the lug of the oscillating bracket is in the inner groove of the cam wheel and the drive 80 pinion is in mesh with the pinion on the engine shaft. Fig. 6 is another view similar to Figs. 4 and 5 showing the relative position of parts when the lug of the oscillating bracket is traveling in the outer groove 85 and the rewinding pinion is in mesh with the motor driven gear wheel and the pinion on the engine shaft. In this view the lug of the bracket is about to leave the rewinding 90 groove and enter the keeper slot for resetting. Fig. 7 is a detail sectional view showing the interior construction and arrangement of springs within the spring motor casing. Fig. 8 is an enlarged detail 95 sectional view of the cam wheel.

Similar reference characters designate corresponding parts throughout the several figures of the drawings.

With particular reference to the details of construction shown in the accompanying 100 drawings, it will be observed that the reference letter E designates an internal combustion engine including the usual frame portion F and having the usual engine shaft S.

Upon the frame F of the engine or vehicle, and in front of the cylinders is preferably arranged a main supporting frame 1 which carries at one side thereof a spring motor 2, and also supports an oscillating bracket element 3 mounted upon a stub-shaft or axle 4. Arranged upon the said 105 axle 4, concentric with the oscillating bracket

3 is a main motor driven gear 5 meshing with an intermediate transmission gear 6 which gears with the driving pinion 7 of the motor 2. The said oscillating bracket 5 element 3 which is pivoted on the axle 4, preferably includes a bifurcated portion comprising the gear supporting members 8 and 9, and an arm portion 10 extending to one side of the members of the bifurcated 10 portion. The said members 8 and 9 have respectively journalized therein a shaft driving pinion 11 and a rewinding pinion 12, which latter meshes with a reversing pinion 13 journalized in the arm portion 10 of the 15 oscillating bracket. This reversing pinion 13 is always normally in mesh with the motor driven gear wheel 5 and the rewinding pinion 12, and may freely rotate when the starter is turning the engine shaft 20 through the medium of the pinion 11 in a clockwise direction, since the rewinding pinion 12 during this operation is entirely out of mesh with the pinion 14 carried by the engine shaft. The reversing pinion 13 is 25 journaled so that it is relatively movable. That is to say, it is mounted on an axis that may be shifted so as to lift it out of mesh with either the gear 5 or pinion 12 or both, to permit the spring motor to be hand 30 wound by means of a suitable tool engaging with the squared end of the motor shaft 2a. The specific means for mounting this wheel is immaterial, but as an illustration this reversing pinion 13 is shown in the drawings 35 as being provided with a central circular opening 15 which receives an eccentric axle member 16 having connected therewith a suitable handle 17. It will thus be apparent that when the cam or eccentric axle 40 member 16 is in the position shown in the drawings, the reversing pinion is in its normal operative position, but can be easily shifted to an inoperative position by turning the handle 17 to one side.

45 The extreme end of the arm 10 of the oscillating bracket is provided with a laterally projecting lug 18 which is operatively connected with a cam wheel 19. That is to say, the lug 18 carried by the arm of the 50 oscillating bracket element 3 is the means by which the said bracket is oscillated during the rotation of the cam wheel. The said cam wheel is carried upon the main frame 1 by means of an axle shaft 20, and includes a hub portion 21 and an exterior circumferential gear ring 22 meshing with an auxiliary driving pinion 23 mounted on the same shaft 24 with the transmission gear 6. It will thus be apparent that the cam wheel 55 19 is driven by the train of gears 7, 6 and 23, the latter meshing with the exterior gear ring 22.

The working face of the cam wheel 19 is recessed to provide an interior wall 25 and 60 is also provided with an inner driving

groove 26 and an outer rewinding groove 27 which is connected with the said groove 26 and in communication therewith by means of an inlet passage 28 and a separate outlet passage 29, thus forming a substantially 70 continuous cam groove or guideway in which the lug 18 of the oscillating bracket may travel. One wall of the passage 28 is provided with a keeper socket 30 for receiving the lug 18 which is normally guided and 75 held therein by means of a keeper spring 31 having one end fixed as at 32 to the inner cylindrical side wall 25 of the cam wheel. The passage of the lug 18 through the continuous guideway is facilitated by means of 80 a transferring spring 33, one end of which encircles the hub 21 of the cam wheel to which it is affixed, while the free end 34 extends across the outlet portion of the inner groove 26 adjacent the outlet passage 85 29, so that when the lug 18 reaches this passage, it is quickly transferred or shifted to the outer or rewinding groove 27. It will thus be apparent that the normal position of the lug 18 when the oscillating 90 bracket is in its neutral position, as shown in Fig. 4, is in the keeper socket 30, and in order to oscillate the bracket to throw the driving pinion 11 into mesh with the shaft pinion 14, it is necessary to release the lug from the keeper socket and throw it into the inner or driving groove 26.

The release of the lug 18 from the keeper socket, is manually effected by means of a suitable foot lever mechanism designated 100 in its entirety by the numeral 35. This mechanism includes a bell crank lever 36 journaled in a bracket 37 and having a link connection 38 at one end with the rear end 18a of the lug or an equivalent portion 105 of the arm 10 of the oscillating bracket, inasmuch as the said lug 18 is carried thereby. The other end or arm of the bell crank lever 36 is pivotally connected with a longitudinally movable rocker rod 39 110 which connects with a foot pedal 40 pivoted in a suitable bracket 41 to the car body directly in front of the driver's seat. For the purpose of aiding in maintaining the rod 39 and pedal 40 in their normal position a spring 42 may be arranged between the bracket 37 and a collar 43 carried on the rod 39, but if desired, this spring may be dispensed with as the movement of the lug 18 from one groove to the other also moves the bell crank in such a manner that the foot 115 pedal 40 is automatically returned or reset.

When the entire device is in its normal position as shown in Figs. 1, 2, 3, and 4, the driving pinion 11 and rewinding pinion 12 will be out of mesh with the shaft pinion 14, the lug 18 will be in the keeper socket 30, and the foot pedal 40 will be in its normal position as shown in Fig. 2. In order to render the device operative to start the en- 120 125 130

gine, the operator presses the foot pedal 40 which actuates the foot lever mechanism 35 and lifts the lug 18 out of the socket 30 into the inner or driving groove of the cam wheel. Since the cam wheel 19 is geared with the motor 2, the latter will rotate the said cam wheel and cause the lug 18 to follow the path of the arrows in Figs. 4 and 5. At the same instant that the lug 18 is thrown out of the keeper socket, the oscillating bracket element 3 rocks on its pivot and forces the shaft-driving pinion 11 into mesh with the shaft pinion 14, thus spinning the engine shaft and starting the engine. The spring motor then exerts its influence upon the shaft pinion 14 through the medium of the motor driven gear 5, the intermediate transmission gear 6, and the driving pinion 7 of the motor, and for all of this period the driving pinion 11 is in mesh with the motor driven gear 5 and shaft pinion 14, and the lug 18 is traveling in the inner groove 25.

Since the initial action of the starter sets the internal combustion engine E in motion, the shaft S of the latter through the shaft-pinion 14 rewinds the spring motor 2 as it continues running. That is to say, after the lug 18 has completed its course through the inner driving groove 26 of the cam wheel, and enters the passage 29, it is thrust into the outer rewinding groove 27 by means of the transferring spring 33. This action automatically throws the driving pinion 11 out of mesh with the shaft pinion 14, and throws the rewinding pinion 12 into mesh therewith as shown in Fig. 6 of the drawings. The said rewinding pinion 12 thus being in mesh with the shaft pinion 14 receiving power from the engine of the motor car will in turn transmit motion to the reversing pinion 13 which meshes with the motor driven gear wheel 5, and this latter wheel through the gear wheel 6 will turn the motor pinion 7 in a reverse direction to that in which it rotates to affect the starting of the combustion engine, thereby rewinding the spring motor and returning the lug 18 to the keeper socket 30. This movement of the several parts of the device automatically resets the starter for the next operation and returns the oscillating bracket to its normal neutral position as shown in Fig. 4.

In connection with the movement of the lug 18 in the outer groove 27, it will be observed that when the same is about to enter the passage 28, it encounters the bowed portion of the keeper spring 31 which not only has a tendency to aid in shifting the lug from the outer groove toward the inner groove, but has the important function of forcing the said lug into the keeper socket 30 formed in the wall of the passage between these two grooves. This spring 31

therefore provides against the lug 18 going from the outer groove 27 to the inner groove 26 direct without stopping at the resetting point.

The spring motor 2 is especially designed and constructed to provide for spinning the engine shaft a sufficient length of time to insure the starting of the engine, providing, of course, the engine is in proper working condition. By reference to Fig. 7, it will be observed that the spring motor 2 essentially comprises an outer casing 44 and an interior casing 45 provided with a flange 46 and a sleeve 47, the latter embracing the motor shaft 2^a and the former registering with the cylindrical side wall of the outer casing 44. This construction makes possible the use of two coil springs, thereby insuring the motor of double strength. One spring 48 has its outer free end secured as 85 at 49 to the outer casing 44 while its inner ends are fastened as at 50 to the sleeve 47 of the interior casing. The other spring 51 is housed within the inner casing 45 and has its outer free end fastened as at 52 to the flange 45 while its inner end is secured as at 53 directly to the shaft 2^a. The spring 51 will unwind upon the release of the lug 18 from the keeper socket 30, and the spring 48 will do likewise, thus transmitting motion to the motor shaft 2^a with twice the power as either one of the springs could singly.

From the foregoing description, it is thought that the many features and advantages of the present invention will be readily apparent, and it will of course be understood that minor details of construction may be resorted to and various changes in the arrangement of the gearing may be made without sacrificing any of the advantages of the invention, or departing from its spirit or scope of the appended claims.

I claim:

1. An automobile engine starter comprising in combination with the engine shaft having a pinion thereon and a spring motor, of a supporting frame, a movable carrier mounted on said frame and having pinions, gearing adapted to be actuated by said motor and in constant gear with one of said pinions, shifting means geared with said motor and operatively connected with said carrier for oscillating the same, and manually controlled means for rendering the shifting means and motor operative.

2. An automobile engine starter comprising in combination with the engine shaft having a pinion thereon, a spring motor, gearing actuated by said motor, a support, a normally inoperative oscillating bracket element carried by said support, pinions carried by said bracket, one of which is in constant gear with said gearing, and manually controlled means including a cam

- wheel for automatically causing said pinions to alternately mesh with the pinion on the engine shaft.
3. An automobile engine starter comprising in combination with the engine shaft having a pinion thereon and a spring motor, a motor driven gear having a fixed axis, an oscillating bracket arranged concentric with said motor driven gear and having pinions adapted to alternately mesh with the pinion on the engine shaft for permitting the spring motor to rotate the latter and then be rewound, and means for automatically controlling the movement of said oscillating bracket.
4. An automobile engine starter comprising in combination with the engine shaft having a pinion thereon, and a spring motor, of a supporting frame, an oscillating bracket element having one end pivotally mounted on said frame and having spaced apart pinions at its other end, gearing adapted to be actuated by said motor, and means for automatically shifting said bracket to cause said pinions to alternately engage with the pinion on the engine shaft.
5. An automobile engine starter comprising in combination with the engine shaft having a pinion thereon and a spring motor, of a supporting frame, an oscillating bracket pivotally suspended from said frame and having pinions, gearing adapted to be actuated by said motor, cam means geared with said motor and operatively connected with said bracket for oscillating the same, and manually controlled means for rendering the cam means and motor operative.
6. An automobile engine starter comprising in combination with the engine shaft having a pinion thereon, of a supporting frame, a spring motor carried by said frame, an oscillating bracket element having a bifurcated portion and an arm, a shaft driving pinion and a rewinding pinion respectively carried by each member of said bifurcated portion, a lug carried by the arm of the bracket, gearing connected with said motor and including a reversing pinion, and manually controlled means including a cam wheel for throwing said shaft driving pinion into mesh with the gearing and pinion on the engine shaft, and automatically throwing the said shaft-driving pinion out of mesh and the rewinding pinion into mesh with the gearing and pinion on the engine shaft to rewind the spring motor.
7. An automobile engine starter comprising in combination with the engine shaft having a pinion thereon and a spring motor having a driving pinion, of a motor driven gear, an automatically oscillating bracket arranged concentric with said motor driven gear and having pinions adapted to alternately mesh with the pinion on the engine shaft for permitting the spring motor to rotate the latter and then be rewound, and a reversing pinion normally in engagement with the motor driven wheel and capable of being disengaged therefrom.
8. An automobile engine starter comprising in combination with the engine shaft having a pinion thereon and a spring motor having a driving pinion, of a motor driven gear, an automatically oscillating bracket arranged concentric with said motor driven gear and having pinions adapted to alternately mesh with the pinion on the engine shaft for permitting the spring motor to rotate the latter and then be rewound, and a reversing pinion carried by the oscillating bracket and normally in engagement with said motor driven wheel, and means for throwing said pinion out of mesh with the motor driven gear.
9. An automobile engine starter comprising in combination with the engine shaft having a pinion thereon, of a supporting frame, a spring motor carried thereby, a gear train connected with said motor, an oscillating bracket also carried by said frame, a lug on the bracket, pinions mounted on said bracket, a cam wheel having grooves for receiving the lug on the bracket and operatively connected with the motor, and a manually controlled lever connected with said lug.
10. An automobile engine starter comprising in combination with the engine shaft having a pinion thereon, of a supporting frame, a spring motor carried thereby, a gear train connected with said motor, an oscillating bracket also carried by said frame, a lug on the bracket, pinions mounted on said bracket, a cam wheel having concentric communicating grooves and a keeper socket, the latter normally holding said lug and the former directing its movement, a gear carried by the cam wheel and connected to the motor, and a manually controlled lever for ejecting said lug from the keeper socket.
11. An automobile engine starter comprising in combination with the engine shaft having a pinion thereon, of a frame, a motor, a motor driven gear, a motor driven cam wheel having concentric communicating cam grooves, and a keeper socket, an oscillating bracket element mounted concentrically with said motor driven gear, a lug carried by said bracket normally held in said keeper socket, pinions carried by said bracket, and manually controlled means for releasing the lug from the keeper socket to automatically shift the pinions carried by the bracket element into mesh with the motor driven gear and pinion on the engine shaft to rotate the latter and rewind and reset the motor.
12. An automobile engine starter comprising in combination with the engine shaft having a pinion thereon, of a frame, a motor, a motor driven gear, a motor driven cam wheel having concentric communicating

grooves and a keeper socket between said grooves, said cam wheel also having a keeper spring and a transferring spring, and a gear ring operatively connected with said motor,
5 an oscillating bracket element concentrically mounted with said motor driven gear, a lug carried by said bracket and normally resting in said keeper socket, pinions carried by said bracket, and manually controlled means for
10 ejecting the lug from the keeper socket.

13. An automobile engine starter comprising the combination with an engine shaft having a pinion thereon, of a frame, an oscillating bracket element carried by said frame
15 and having pinions for alternately meshing with the pinion on the engine shaft, gearing for connecting with the pinions carried by the bracket, a cam wheel for controlling said

bracket, and a spring motor connected with said gearing and cam wheel, said spring 20 motor including an exterior casing, a motor shaft, an interior casing formed with a sleeve and mounted on said shaft, a coil spring having one end fixed to the outer casing and its other end fixed to said sleeve of the interior casing, and a second coil spring mounted within the interior casing and having one end fixed therewith and the other end secured to said shaft.

In testimony whereof I hereunto affix my 30 signature in the presence of two witnesses.

JOHN WESLEY HOFFNER.
